J. F. DRINKWATER,
RAILWAY BRAKE APPLIANCE,
APPLICATION FILED OCT. 30, 1918.

1,328,138.

Patented Jan. 13, 1920.

Inventor
J. F. DRINKWATER.

By Attorney

UNITED STATES PATENT OFFICE.

JAMES F. DRINKWATER, OF WILLARD, OHIO.

RAILWAY-BRAKE APPLIANCE.

1,328,138.

Specification of Letters Patent. Patented Jan. 13, 1920.

Application filed October 30, 1918. Serial No. 260,356.

To all whom it may concern:

Be it known that I, JAMES F. DRINKWATER, a citizen of the United States, residing at Willard, in the county of Huron and State of Ohio, have invented certain new and useful Improvements in Railway-Brake Appliances; and I do hereby declare the following to be a full, clear, and exact description of the invention, such as will enable others skilled in the art to which it appertains to make and use the same.

My invention relates to improvements in railway brake appliances.

An important object of this invention is to provide an apparatus of the character described adapted for attachment to cars for use in place of the usual chain structure connecting the brake mechanism with the operating means therefor.

A further object of this invention is to provide an efficient manually operated brake operating structure adapted for use in conjunction with an air brake system.

A further object of the invention is to provide an apparatus of the character described, which is of highly simplified construction, reliable in use, and easy to install on standard rolling stock.

Other objects and advantages of the invention will be apparent during the course of the following description.

In the accompanying drawings forming a part of this specification and in which like numerals are employed to designate like parts throughout the same,

Figure 1 is a side elevation of an apparatus embodied in my invention,

Fig. 2 is a vertical longitudinal section through the same,

Fig. 3 is a horizontal section taken on line 3—3 of Fig. 1,

Fig. 4 is a section taken on line 4—4 of Fig. 1,

Fig. 5 is a section taken on line 5—5 of Fig. 1,

Fig. 6 is a section taken on line 6—6 of Fig. 3, and

Fig. 7 is a vertical section taken on line 7—7 of Fig. 3.

In the drawing, wherein for the purpose of illustration is shown the preferred embodiment of my invention, the numeral 10 generically designates an apparatus embodied in my invention. The same comprises a rectangular base 11 having longitudinally extending side walls 12 and verti-

cally disposed end walls 13 secured to the base 11 by bolts 14. A vertically disposed brake staff 15 has its lower end journaled in a bearing 16 carried by the rear portion of 60 the base 11. As shown in Fig. 3, the brake staff 15 has a worm 17 arranged thereon and meshing with a worm gear 18 carried by a horizontally disposed shaft 19. A set screw 20 provides a rigid connection between the worm gear 18 and the horizontally disposed shaft 19. The shaft 19 extends longitudinally of the base 11 and has its ends journaled in bearings 21 carried by the vertical end walls 13. As clearly shown 70 in Fig. 2, the forward end of the base 11 extends beyond the forward end wall 13 and forms a longitudinally extending guideway 23. The guideway 23 includes side walls 24 and a base 26. A rack bar 27 having 75 teeth 28 is received in the guiding member 23 and is adapted to partake of a reciprocatory movement therein.

As clearly shown in the several figures, the rack bar 27 is adapted to mesh with a relatively large worm gear 29 carried by the horizontally disposed shaft 19 at its forward end portion. As shown in Fig. 6, the forward end portion of the shaft 19 extends into a centrally disposed longitudinally extending rectangular opening 30 in the worm gear 29, and is held therein by a set screw 31. It will be apparent that the rotation of the brake staff 15 causes the horizontal shaft 19 to partake of a like movement and 90 thus actuate the rack bar 27. As clearly shown in Fig. 2, a loop 32 is arranged parallel to the rack 27 and is provided at one end thereof with an eyelet 33 for connecting the loop 32 with the braking mechanism of the 95 car. The loop 32 is provided with a longitudinally extending opening 34 receiving an L-shaped arm 35 carried by the rear end of the rack bar 27. Upon the rearward movement of the rack bar 27, the L-shaped arm 100 35 will engage the rear end of the loop 32 and draw the same rearwardly. The rearward movement of the loop 32 causes the actuating of the braking mechanism, which upon return of the loop, is automatically returned to a non-operative position by a spring mechanism as is usual in brake structures. In the use of my invention, it will be apparent that the usual air brake system may be applied to the braking mechanism 110 and be operated in conjunction with the apparatus above described. The applying of

the brakes by air pressure will cause the loop 32 to move rearwardly independently of the rack bar 27.

With reference to the foregoing, it will be apparent that I have provided a highly efficient and reliable brake operating structure adapted for attachment to cars without in any way interfering with the operation of the air brake system.

10 While I have shown and described the preferred embodiment of my invention, it is understood that I may make such minor changes in arrangement and construction of parts, as will remain within the spirit of 15 the invention and the scope of the appended claims.

Having thus described my invention, what I claim is:—

1. An apparatus of the character described comprising a base; a horizontally disposed shaft carried thereby; a gear carried by said shaft; a brake staff having one end thereof journaled in said base; a gear carried by said staff and meshing with the gear carried by said shaft; a rack bar slidably carried by said base; a worm gear carried by said shaft and meshing with said rack bar; an elongated loop arranged parallel with the rack bar and having connection with a brake mechanism; and an arm extending from said rack bar and having sliding connection with said loop, said rack bar being adapted to be operated by the rotation of said brake staff.

35 2. An apparatus of the character described comprising, a base; a horizontally disposed shaft carried thereby; operating means for said shaft; a worm gear carried by said shaft; a rack bar slidably carried by said base and meshing with said worm gear; an elongated loop arranged parallel to said rack bar; and an L-shaped arm slidably connected with said elongated loop and extending from said rack bar, said elongated loop being adapted to be operated by the operation of said rack bar.

45 3. An apparatus of the character described

comprising, a base; a horizontally disposed shaft carried thereby; a gear carried by said shaft; a vertically disposed brake staff 50 having one end thereof journaled in said base; a worm gear carried by said staff and meshing with the gear carried by said shaft; a rack bar carried by said base; a worm gear carried by said horizontally disposed shaft and meshing with said rack bar; and an elongated loop having sliding connection with said rack bar and arranged parallel thereto, said rack bar being adapted to operate said loop.

4. An apparatus of the character described comprising, a base; a shaft carried thereby; operating means for said shaft; a worm gear arranged on said shaft; a guideway extending forwardly from said base; a rack 65 bar carried by said guideway and having connection with the worm gear carried by said shaft; an elongated loop arranged parallel to said rack bar and having sliding connection therewith, said elongated loop 70 being connected with a brake mechanism and being adapted to be operated by the actuation of said rack bar.

5. An apparatus of the character described comprising a base; a horizontally disposed 75 shaft carried thereby; a worm gear carried by said shaft; a longitudinally extending guideway carried by said base; a rack bar slidably arranged in said guideway and meshing with said worm gear; operating 80 means for said shaft; an elongated loop arranged parallel to said rack bar; and an L-shaped arm extending from said rack bar and having sliding connection with said elongated loop, said elongated loop being 85 adapted to be operated by the actuation of said rack bar.

In testimony whereof I affix my signature in presence of two witnesses.

JAMES F. DRINKWATER.
